UNITED STATES PATENT OFFICE.

SAMUEL COHEN, OF BROOKLYN, NEW YORK, ASSIGNOR TO OSODAMPA CORPORATION, OF NEW YORK, N. Y., A CORPORATION OF NEW YORK.

RADIOFREQUENCY AMPLIFIER.

Application filed September 8, 1924. Serial No. 736,603.

To all whom it may concern:

Be it known that I, SAMUEL COHEN, a citizen of the United States, residing at Brooklyn, in the county of Kings and State of New York, have invented a certain new and useful Improvement in a Radiofrequency Amplifier, of which the following is a specification.

My invention relates broadly to the amplification of feeble currents by electron tube circuits and more particularly to a radio frequency amplification system of great sensitivity.

One of the objects of my invention is to provide a radio frequency amplification system for the reception of high frequency signaling currents, wherein both straight amplification and regenerative amplification is secured without distortion of the received signals.

Another object of my invention is to provide a combined direct amplifying electron tube system and a regenerative amplifying electron tube system associated with a detector circuit with means for controlling the regenerative amplification for preventing undesired reaction with other electron tube circuits in the system.

Still another object of the invention is to provide a construction of regenerative compensator for connection in the last stage of amplification in a radio frequency amplifier immediately preceding the detector circuit for securing a large amplitude of radio frequency energy which may be impressed upon the input circuit of the detector for operating a responsive device.

A further object of the invention is to provide a construction of coupling system interposed between a radio frequency amplification system and a detector system for increasing the energy in the detector circuit by regenerative action with means for preventing regenerative effects in the amplification stages preceding the coupling system and allowing regeneration below a point of oscillation in the coupling system for impressing the received signaling energy at large amplitude upon the detector.

Other objects of my invention will be understood from the specification herein-after following by reference to the accompanying drawing showing a diagrammatic arrangement of my radio frequency amplification system.

Heretofore in the art it has been proposed to regulate regeneration in a radio frequency amplifier by means of a potentiometer shunted across the filament circuit of the amplifier with a connection to the grid electrodes of the several tubes of the system from a variable contact member upon the potentiometer.

With the potentiometer method, regeneration can be stopped when the grids of the amplifier tubes are maintained at positive potential. This method of control is not an efficient one, since by causing the grids to be at a positive potential a large drain on the "B" battery is effective. At the same time distortion of the signaling energy is brought about and the amplification is considerably reduced. With the regenerator compensator method of my invention these disadvantages are overcome since the grid electrodes are maintained at all times at a negative potential. The amount of regeneration is controlled by the amount of a counter E. M. F. introduced in the circuit, whose amplitude may be equal or greater than the regenerative E. M. F. In all cases it can be made equal but opposite in phase to the regenerative E. M. F.

By the arrangement of the regenerative compensator the sensitivity of the system is greatly increased. The regenerative action of a tube is employed at such an adjustment that this regenerative action operates in such a manner as to prevent distortion in the system. To do this, I prefer to make or allow the amplifying tube next to the detector tube to operate in a state of regeneration. At the same time I provide means for preventing regeneration by self excitation in the tube circuits immediately preceding the regenerative compensator. I employ a variable capacity of a special character which is connected with an independent winding forming part of the primary circuit of the inter-valve coupling transformer. By means of the combination of this special capacity and inductance, I can control the amount of regeneration as desired. The grid electrode of the tube in the regenerator coupling circuit is maintained permanently at negative potential.

The regenerative compensator consists of two parallel electrodes or plates whose capacity is equal to approximately five times the grid-plate capacity. A movable mem-

ber or electrode is placed within the center of the parallel plates, which movable plate has an area slightly larger than the area of the parallel plates. When the entire area 5 of the movable plate is in the electrostatic field of the parallel plates, the electrostatic capacity between the parallel plates is reduced to a minimum by virtue of the circuit arrangement. The regenerative action is 10 obtained in the stage of amplification immediately preceding the detector. The output circuit of this tube contains a pair of coils forming the primary winding of the coupling transformer. The two coils have the 15 same number of turns but are wound in opposite directions. The amount of regeneration in the circuit is controlled by the magnitude of the counter E. M. F. introduced in the circuit and this is adjustable 20 over a wide range by means of the special condenser and one of the coupling inductances.

Referring more particularly to the wiring diagram my invention is illustrated as 25 applied in connection with three stages of tuned radio frequency amplification at a radio receiver although it will be understood that more or less stages may be employed as desired. The antenna is represented by reference character 1 connected with ground system 2 with primary winding 3 of the tuning transformer in circuit therewith. Secondary winding 5 is inductively related to primary winding 3 and 30 is tuned by variable condenser 6 to the frequency of the signals desired to be received. The first stage of radio frequency amplification includes electron tube 7 having filament electrode 8, grid electrode 9, and 35 plate electrode 10. The input circuit of the tube across grid electrode 9 and filament electrode 8 is connected with the tuned circuit 5 and 6. The output circuit of tube 7 includes primary winding 11 of the radio 40 frequency coupling transformer 15 with one end of the winding 11 connected to a source of B battery potential represented at 14. The secondary winding 16 of coupling transformer 15 is tuned by variable condenser 17 and connects to the input circuit of electron tube 18 forming the second 45 stage of radio frequency amplification. The output circuit of tube 18 includes primary winding 19 of coupling transformer 20 and source of B battery potential 14. The tubes 50 7 and 18 are connected in such manner that the tendency of the tubes to oscillate or regenerate is annulled. This is accomplished by employing the principle set forth in detail in my copending application Serial No. 736,602, filed Sept. 8, 1924, wherein the resistances and capacities R_4 and C_4 are electrically related to the inherent tube capacities for shifting the phase of interfering 55 currents with respect to the phase of the

signaling currents. I therefore provide a radio frequency amplifier wherein a number of stages operate as straight amplifiers without regeneration or oscillation. Tube 23, however, which immediately precedes the 70 detector tube 33 is arranged for regenerative amplification. The input circuit of tube 23 is formed by secondary winding 21 of coupling transformer 20 tuned by variable condenser 22. Regeneration in the tube 75 circuit 23 is controlled by means of the regenerator compensator 28 comprising parallel electrodes or plates 30 and 31 between which the movable member or electrode 29 is positioned in such manner that the spacial relation with plate 31 or plate 30 may be regulated at will. A radio frequency coupling transformer 26 is connected in the output circuit of tube 23. This coupling transformer includes a pair of primary windings 24 and 25 each having the same 80 number of turns but wound in opposite directions. Each of the primary windings 24 and 25 are cumulatively coupled with secondary winding 27 which connects through grid leak and grid condenser 32 with the input circuit of detector tube 33. The responsive device 34 is operated in the output circuit of the detector tube 33 and tap connection 35 taken from B battery 14. The filaments of all of the tubes are heated from battery 12. A by-pass condenser 36 is shunted across batteries 12 and 14.

Referring more particularly to the regenerator compensator 28, the primary winding 25 is connected with the movable plate or electrode 29. The fixed plate 31 is connected with a point in the output circuit of tube 23 at one end of the oppositely wound primary coil 24. The fixed plate or electrode 30 is connected indirectly with the opposite end of primary winding 24 through primary winding 19 of coupling transformer 20 in the output circuit of the preceding stage of radio frequency amplification formed in circuit with tube 18. The plate 29 has a larger area than plates 30 and 31. The magnitude of the counter E. M. F. introduced in the circuit is adjustable over a wide range by moving plate 29 either toward or away from the plates 30 and 31. The regenerator compensator is so proportioned that the tube 23 will operate at maximum efficiency in condition of regenerative amplification for increasing the amplitude of the received energy for detector tube 33.

While I have described my invention as applied to a three stage radio frequency amplifier it will be understood that the principle of my invention may be used with many arrangements of multistage amplifiers where a number of tubes are operated with straight amplification while others of the tubes are operated with regenerative ampli- 125 130

ification. The circuits formed by resistances and capacities R_4 and C_4 prevent regeneration in tubes 7 and 18 while the regenerator compensator 28 permits regeneration under control of the operator in tube 23, the circuits cooperating to maintain the entire system in stable condition for the reception of signals without distortion. I desire that it be understood that modifications of the circuit arrangements may be made and that I intend no limitations upon the invention other than are imposed by the scope of the appended claims.

What I claim and desire to secure by Letters Patent of the United States is as follows:

1. A radio frequency amplifier comprising in combination a plurality of electron tubes each having input and output circuits interlinked one with the other, a detector connected with the output circuit of one of said tubes, means connected between the input and output circuits of said tubes immediately preceding the tube next adjacent said detector for preventing regenerative amplification and a three electrode condenser having two of its electrodes connected between the output circuit of said tube immediately preceding the tube next adjacent said detector and the output circuit of said tube next adjacent said detector, and a connection between the third electrode of said condenser and a separate winding magnetically coupled with the input circuit of said detector for permitting regenerative amplification whereby received signaling energy may be impressed at relatively large amplitude upon said detector.

2. A radio frequency amplifier including a detector, comprising in combination a plurality of electron tubes each having input and output circuits interlinked one with the other, a coupling transformer interlinking the output circuit of one of said tubes with said detector, said transformer having a pair of primary windings, one of said windings being wound in a direction opposite to the direction of the other of said windings, an electrostatic coupling between one of said windings and the output circuit of a preceding one of said tubes and means electrostatically coupling the other of said primary windings with said aforementioned electrostatic coupling.

3. A radio frequency amplifier including a detector, comprising in combination a plurality of electron tubes each having input and output circuits interlinked one with the

other, means for coupling one of said tubes with said detector comprising a pair of oppositely wound primary coils coupled with a secondary coil connected with said detector, a three electrode variable capacity connected between said primary coils and a point in the output circuit of a preceding one of said electron tubes for controlling the magnitude of a counter electromotive force introduced in said tube circuit by said oppositely wound primary coils whereby to regulate the amount of regenerative amplification produced by said tube.

4. A radio frequency amplifier including a detector, comprising a plurality of electron tubes each having input and output circuits connected one with the other, means connected with a number of said tubes for preventing regenerative action, means coupling the output circuit of another of said tubes with said detector, said means comprising a pair of oppositely wound primary coils coupled with a secondary coil, a pair of condenser plates, a connection between one of said plates and one of said primary coils, a connection between the other of said condenser plates and a point in the output circuit of a preceding one of said tubes and an intermediate condenser plate positioned between said pair of condenser plates and connected with one terminal of said other primary coil whereby regenerative amplification is secured in said last mentioned tube.

5. A radio frequency amplifier including a detector comprising a plurality of electron tubes each having input and output circuits connected one with the other, means connected with a number of said tubes for preventing regenerative action, means coupling the output circuit of another of said tubes with said detector, said means comprising a pair of oppositely wound primary coils coupled with a secondary coil, a pair of condenser plates, a connection between one of said plates and one of said primary coils, a connection between the other of said condenser plates and a point in the output circuit of a preceding one of said tubes, a separate condenser plate connected with the other of said primary coils greater in size than said aforementioned condenser plates positioned intermediate said condenser plates and adapted to be moved toward or away from either of said aforementioned condenser plates for controlling regenerative amplification in said last mentioned tube.

SAMUEL COHEN.
